(57) **CLAIM**

The ornamental design for a swim cap with an applied pattern as shown and described.

DESCRIPTION

FIG. 1 is a front perspective view of a swim cap with an applied pattern as shown worn by a user, showing my new design;

FIG. 2 is a left side elevational view of the swim cap with an applied pattern;

FIG. 3 is a right side elevational view thereof;

FIG. 4 is a front elevation view thereof;

FIG. 5 is a rear elevation view thereof; and,

FIG. 6 is a top plan view thereof.

The broken line outline of the partial human figure in FIG. 1 assists in illustrating how the swim cap with an applied pattern may appear when in a position of use, but forms no part of the claimed design.
